UNITED STATES PATENT OFFICE.

ANDREW MCNAIR COYLE, OF WASHINGTON, DISTRICT OF COLUMBIA.

STEAM-TRAP.

SPECIFICATION forming part of Letters Patent No. 333,924, dated January 5, 1886.

Application filed September 9, 1885. Serial No. 176,623. (No model.)

To all whom it may concern:

Be it known that I, ANDREW MCNAIR COYLE, of Washington city, District of Columbia, have invented a certain new and useful 5 Improved Steam-Trap for Heating Systems and for other Purposes, of which the following is a specification.

In the class of apparatus to which my invention specially relates the water of condensation from a system of piping through which steam circulates is delivered into a drip-tank or receiving-chamber by gravity and the pressure of the steam in the pipes, and conveyed therefrom and injected into the boiler. Various apparatus for the purpose have been devised, some being now in general use. In all of them, however, so far as I am aware, the working depends on the motion of some part of the apparatus which opens and closes a steam-valve. In other words, in this class of apparatus a valve for admitting and cutting off steam from the vacuum-chamber and some moving device actuated by the rise and fall of water in said chamber have always been used. Such a construction is expensive and more or less complicated, the valves wear and get out of order, and the moving parts are liable to become deranged.

The object of my invention, having reference to its application to steam-heating systems, is to accomplish the perfect and automatic removal of the water from the drip-tank and its injection into the boiler without the use of any steam-valve, float, or moving device. Obviously the utmost simplicity of structure will be attained by such construction, the cost of manufacture reduced to a minimum, and the liability of derangement and necessity for repairs practically eliminated. Aside from these, there are other advantages attending the use of my apparatus, which will appear below.

In the accompanying drawings, Figure 1 is an elevation, partly in section, illustrating my invention. Figs. 2 and 3 are views showing other arrangements acting on the same principle, and Figs. 4, 5, and 6 are views showing some modified ways of making the pipe-connections.

50 While the structure shown in the drawings

is practical and effective, I do not limit myself to the specific arrangement, as obviously any engineer might make variations in the structure without departing from the principle of my invention.

55 In Fig. 1, A represents the drip-tank or receiving-chamber. It may be made in any suitable way. I prefer to cast it in globular form, and have so represented it. Water enters the drip-tank by pipe B, (shown as leading to the bottom,) and steam enters by pipe C, (shown as connected at the top.) A vertical pipe, D, in connection with the drip-tank through the pipe B, is shown as connecting with the top of a chamber, E, which may be 60 called the "vacuum" or "condensing" chamber, and is preferably a globular casting. From the bottom of chamber E a pipe, F, leads to the boiler, and is provided with an ordinary check-valve at f, opening toward the 65 boiler. The chamber A is connected with pipe D by means of the bent pipe G, (shown as connected near the top of the drip-tank,) carried down outside nearly to the level of the bottom of said tank, then turned, carried 70 up, and connected with pipe D at a point preferably above the level of the orifice g. Vacuum-chamber E may be connected with the steam-space of the boiler by pipe H, having an ordinary cock, h. The chamber E is 75 also provided with the check-valve I, which may be regulated by a screw, as shown. A pipe, K, provided with a check-valve, k', and a cock, k, may be used, if desired, to connect chamber E with some water-supply, for a purpose presently described.

80 The action is as follows: Water enters chamber A by pipe B and steam by pipe C. The steam passes through pipes G and D into chamber E. When the water in chamber A 85 rises to the opening g, pipe G becomes filled and the steam is cut off from chamber E. The steam-pressure in A, acting against the vacuum caused by condensation in E, will now cause the water in A to ascend to E by way of pipes 90 B and D. Obviously the water in the bent pipe G is the hydrostatic equivalent of that in the chamber A and pipes B and D. The water in the shorter limb of pipe G will therefore have the same level as that in chamber A. 100

The lower part of pipe D is preferably enlarged, so as to amply supply water to the upper portion, as otherwise the condition of equilibrium might be disturbed. When the water-level in the shorter limb of pipe G and chamber A falls to the bend g' , the conditions of equilibrium no longer exist. The water in pipe G will therefore be immediately drawn into pipe D, thus opening a passage for the steam in A, which passes through pipes G and D and makes the pressure in E equal or nearly equal to the pressure in A, so that the water in E flows out through pipe F into the boiler. The apparatus remains in this condition until the steam is again cut off from E by pipe G becoming filled, when the action above described is repeated.

The outward-opening adjustable check-valve I on the chamber E is to allow any air which may collect in the apparatus, together with a little steam, to be blown out whenever the pressure in E is greater than atmospheric pressure. Ordinarily the valve I is so adjusted as to allow only a small escape; but it may be opened to its full capacity in starting the apparatus when full of air.

The pipe H, connecting chamber E with the steam-space of the boiler, is used to admit steam to blow out the air from chamber, in order to produce a vacuum therein in case the lower steam-passage is filled with water before the apparatus is started. This pipe is only used to start the apparatus when the steam-pressure is not sufficient to lift the water from A to E against atmospheric pressure. Otherwise the apparatus starts automatically.

When cock k is opened, water flows into chamber E through pipe K whenever condensation takes place, so that the apparatus can be used as a feed-water device while performing its regular functions.

If pipe G is not full when condensation takes place in chamber E, the water in that pipe may be drawn out before chamber A is emptied.

Various devices may be used to insure the filling of pipe G. For instance, as shown in Fig. 1 at g^2 , the connection of pipe G with chamber A may be elongated. Water then flows to the full capacity of the pipe as soon as it overflows the opening g^2 . Or the arrangement shown in Fig. 2, which I greatly prefer, may be used. In that arrangement the pipe G is extended down from its point of connection with the pipe D to a manifold coupling, g' , then up and connected with the steam-pipe C. Obviously this structure is the equivalent of that shown in Fig. 1. A siphon-pipe, S, is also connected with the manifold coupling g' , is carried up, then returned at s , and connected with the tank A. The action of this device is as follows: When the water in chamber A rises to the bend s of pipe S, siphoning takes place through pipe S from tank A, and pipe G is at once filled. When the water in A falls below the connec-

tion s of the tank with siphon, the conditions described in connection with Fig. 1 exist, and when the level of water in A reaches the bend g' or the manifold coupling, the water will be drawn from pipe G and steam will again pass to E. Or, as shown in Fig. 3, the siphon may be made in pipe D, in which case the entire volume of water passes through pipe G. Here the pipes C and G and the manifold coupling 75 are as illustrated in Fig. 2; but in this case the pipe G transfers all the water, instead of only a part, as in the other arrangements. The pipe D, which rises from pipe B, is returned at s and connected with the manifold 80 coupling g' , performing the functions of both water-transfer pipe D and siphon S in Fig. 2. When water rises in pipe D and in the tank A to the level of the bend s , siphoning takes place from pipe B through D into g' , and continues until chamber A is empty. Obviously the arrangement of these pipes may be changed. For example, instead of connecting pipes B and D, as in Figs. 1, 2, and 3, pipe D may be connected at the top of chamber A 85 and extended down inside the chamber, as shown in Fig. 4, and pipe G may connect with D, either higher or lower than represented in Figs. 1, 2, and 3, (see Fig. 5, where it is shown as connected lower in full lines, and 90 where the dotted lines indicate that the pipe may be extended up and connected with chamber E,) and the siphon in Figs. 2 and 3 may be connected at any point with pipe G, or with chamber A, as shown in Fig. 6, even though 95 the point of connection with A be below the bend g' , in which latter case the water will empty from the siphon into A, instead of into G, when the level in A falls below the connection of the siphon with pipe G. These and 100 other changes which do not depart from or change the principle of operation will readily be conceived by those skilled in the art as adapting the apparatus or any part thereof to purposes other than those herein described.

In placing this apparatus in house-heating systems it may be connected in either of two ways. In cases where the return-pipe from the radiators can be conveniently brought 115 into the boiler-room, the drip-tank is placed below the boiler and connected directly with the steam-space, the condensing-chamber being hung above the boiler. The distance of the drip-tank below the boiler-level is added 120 to the fall of the returning water; or, in other words, this arrangement is equivalent to placing the boiler lower than it really is. In other cases the drip-tank is placed below the radiators and connected with the steam-supply 125 pipe, the condensing-chamber being hung sufficiently high to give fall to the returning water. The weight of a column of water equal to the distance of the condensing-globe above the boiler is added to the pressure in the radiators to drive the returning water into the boiler. In other words, this arrangement is 130

equivalent to placing the radiators higher than they really are.

As the water is lifted from A to E by steam-pressure acting against a partial vacuum, the distance water can be lifted by this apparatus is greater than the height of a column equal to the steam-gage pressure. It is therefore easily seen that the drip-tank may be placed so far below the radiators, or the condensing-chamber so high above the boiler, that the pressure of the column of water, acting to force water of condensation from the radiators into the drip-tank, or from the condensing-chamber into the boiler, will be greater than the difference of pressure between the boiler and radiators of any properly-constructed system.

The characteristic and distinguishing feature of my invention is the cutting off of steam from and the admission of steam to the vacuum-chamber by means of a fluid seal, the arrangement being such that water may be automatically and periodically elevated directly from the drip-tank by steam-pressure acting against the vacuum in the upper or vacuum chamber. So far, therefore, as this broad feature is concerned, I consider any apparatus operating in that way and on the same principle as within the scope of my invention.

So far as I am aware, I am the first to connect the drip-tank with a steam-supply, and I consider this an important feature of my invention, which may not necessarily depend on other parts of the apparatus.

So far as I am aware, I am the first to use an intermitting siphon as a means of periodically introducing a sealing-liquid into a steam-pipe, and I consider this an important feature of my invention, which may not depend on other parts of the apparatus.

I have described my invention with particular reference to its application to steam-heating. It may also be used for pumping, and for other liquids than water, particularly with very low steam-pressure, as with the exhaust-steam from engines.

I claim as my invention—

1. The combination of the chamber A, the drip or water-supply pipe leading thereto, an open connection from a source of steam-supply, also leading thereto, the upper or vacuum chamber, the water-transfer pipe connecting the two chambers, and a liquid-seal pipe interposed between the two chambers, substantially as set forth, whereby water is elevated from the lower to the upper chamber by the steam-pressure acting against a vacuum.

2. The combination of the tank A, the chamber E, the transfer-pipe connecting them, the seal-pipe interposed between the two chambers, and additional means, substantially such as described, for insuring the prompt filling of the seal-pipe when the liquid reaches a given height in the tank A.

3. In a steam-heating system, the combina-

tion of the tank A, an open connection between said tank and a boiler or source of steam-supply, the drip-pipe of the heating system leading to said tank, the upper or vacuum chamber, E, the transfer-pipe connecting the two chambers, the seal-pipe interposed between the two chambers, whereby the passage of steam from the lower chamber to the upper chamber is alternately prevented and permitted, as set forth, means for insuring the prompt filling of said seal-pipe when the liquid reaches a given height in the tank A, and a water-return pipe leading from the upper chamber to the steam-boiler.

4. In a steam-heating system, the combination of the chamber A, the drip-pipe, the vacuum-chamber E, the transfer-pipe connecting them, the open connection between the tank A and the source of steam-supply, and means for periodically elevating the water which accumulates in the tank by the pressure of the steam acting against a vacuum, as set forth.

5. In a steam-heating system, the combination of the drip-tank A, the drip-pipe, an open connection between said drip-tank and the steam-boiler, the upper chamber, E, a pipe leading therefrom to the boiler, and pipe-connections between the upper and lower chambers.

6. The combination, in a steam-heating system, of the drip tank, the drip-pipe leading thereto, an open connection between the drip-tank and a steam-boiler, the upper or vacuum chamber, a water-transfer pipe connecting the vacuum-chamber and drip-tank, and the bent water-seal pipe interposed between said water-transfer pipe and the drip-tank, substantially as described, whereby the passage of the steam from the tank to the vacuum-chamber is alternately prevented and permitted and the water elevated by the pressure of the steam acting against a vacuum.

7. The combination of the drip-tank, a fluid-seal pipe connected therewith, and a siphon for insuring the proper filling of the fluid-seal pipe when the water reaches a given level in the tank A, substantially as set forth.

8. In a steam-heating system, the combination of the drip-tank, the drip-pipe, an open connection between a source of steam-supply and the drip-tank, the vacuum-chamber, the transfer-pipe between the two chambers, the seal-pipe interposed between the two chambers, a siphon for insuring the filling of the seal-pipe when the water in the drip-tank has reached a given level, and a water-discharge pipe leading from the vacuum-chamber.

9. The combination of the upper and lower chambers, a water-transfer pipe connecting them, a fluid-seal pipe interposed between said chambers, a connection between the lower chamber and a permanent source of steam-supply of substantially uniform pressure, and a water-seal pipe interposed between the two chambers, for alternately permitting and pre-

venting the passage of steam to the upper chamber, the organization and operation being substantially as herein shown and described, whereby water may be periodically elevated from the lower chamber to the upper one by steam-pressure acting against a vacuum, substantially as set forth.

In testimony whereof I have hereunto subscribed my name this 9th day of September, A. D. 1885.

ANDREW McNAIR COYLE.
